UNITED STATES PATENT OFFICE.

HENRY A. WISE WOOD, OF NEW YORK, N. Y., ASSIGNOR TO AMERICAN HIGH SPEED PRESS COMPANY, OF NEW YORK, N. Y., A CORPORATION OF NEW YORK.

AUTOMATIC FEEDING MECHANISM FOR BED-AND-PLATEN PRESSES.

1,213,567.

Specification of Letters Patent. Patented Jan. 23, 1917.

Application filed January 10, 1911. Serial No. 601,807.

To all whom it may concern:

Be it known that I, HENRY A. WISE WOOD, a citizen of the United States, residing at New York, in the county of New York and State of New York, have invented a new and useful Automatic Feeding Mechanism for Bed-and-Platen Presses, of which the following is a specification.

The principal objects of this invention are 10 to provide a job press with an automatic feed of a practical and efficient character so that the machine will be suitable for all kinds of work for which job presses are ordinarily employed and will also be capable 15 of efficient and satisfactory operation.

The invention also involves an improved and thoroughly practicable pneumatic controlled means for taking the sheets preferably from the bottom of the pile and introducing them into the feed rolls; improvements in the automatic feed, whereby the sheets are fed from the pile by said pneumatic means controlled from the operating shaft of the machine and introduced between 25 the feed rollers with the aid of a device which positively feeds the centers of the sheets and controls the other parts thereof to follow the center accurately into the feed rolls; means for operating and adjusting the 30 latter device and for stopping the pile of sheets in proper position as the feed table moves up to the feeding point; means for accurately adjusting the stop and the said controlling means independently of each 35 other and for adjusting the combined movement of the two separately from the other two adjustments; and improved mechanism for reciprocating the feed table and for adjusting it so as to control its position when 40 discharging a sheet, whereby it will be suitable for sheets of different thicknesses.

The invention also involves several improvements in details of construction of the various parts of the feeding mechanism, as 45 will appear hereinafter.

Reference is to be had to the accompanying drawings, in which—

Figure 1 is a side elevation of a job press with a preferred form of the present improvements applied thereto; Fig. 2 is a plan thereof. Fig. 3 is an end view of a detail. Fig. 4 is a view of the end of the feed bar; Fig. 5 is a sectional view of the same on the line 5—5 of Fig. 4. Fig. 6 is a side view partly in section, on an enlarged scale show-

ing part of the feeding mechanism with the parts in position ready to feed a thin sheet; Fig. 7 is a similar view showing the separation of the bottom sheet and the advance of the pile of sheets into extreme position; Fig. 60 8 is a view similar to Fig. 6 showing the adjustment of the parts for feeding thick sheets; Fig. 9 is a side elevation of the supporting bracket for the feed rolls, and connected parts; and Fig. 10 is an end view 65 thereof.

The invention is shown as applied to a job press having a frame 10, a main shaft 11 provided with pinions 12 transmitting power through gears 13 to the operating 70 shaft 14 as usual. On each gear 13 is a stud connected by a link 16 with a rocker arm 17 for supporting the bed of a printing couple. The links 16 and rocker arms 17 are connected by an eccentric 18 with which is rigidly connected an arm 19. The rocker arm 17 is moved to and from the platen 20 in the usual manner.

On the shaft 14 is a cam 21 which operates a roll 22 on an oscillating arm 23. This arm 80 is fixed on an oscillating rod 24 mounted on a bracket 25 on a cross-piece 26 constituting a part of the frame. A spring 27, also mounted on a bracket on this cross piece, normally forces the arm 23 and the cam roll 22 toward the gear. On the rod 24 is fixed an arm 28 which may be integral with the arm 23 and with which it constitutes a lever. Loosely mounted on the rod 24 is an arm 29. A screw 30 adjustably connects the arms 28 90 and 29 so that by the adjustment of the screw, the angle of these arms to each other can be varied at will. These arms are fixed in adjusted position by means of a screw and nut 31 operating in an obvious manner. The 95 arm 29 is connected by a link 32 with a reciprocating feed table 33 provided with the usual gages and guides. The feed table is mounted on and guided by a pair of inclined rods 34 supported at one end by 100 castings 35 carried by the sucker roll or feed bar 49. These rods are not stationary but are mounted to be adjusted about the transverse axis of the feed bar at one end. They are provided with means for adjusting the 105 other end which changes the angle of the feed table. This adjusting means is shown in the form of a transverse rod 36 connected with the guide rods 34 and a rod 37 extending downwardly and supported at its lower 110

end by a projection 38 from the bracket 25. This rod has a pair of collars 39 adjustable along the same and a set screw for holding the same in adjusted position. By these adjustments the angle of the feed table can be changed and the corresponding adjustment made in the feed thereof, to provide for feeding sheets of different thicknesses or other qualities.

10 On the shaft 14 is a cam 40 adapted to operate a cam roll 41 on an oscillating arm 42. The end of this arm engages the end of a reciprocating rod 43 which is pressed toward the arm 42 and toward the cam by 15 a spring 44. On the rod is a plunger 45 in a cylinder 46. This cylinder is connected by a flexible hose 47 or the like with a stationary casing or cap 48 on the end of a movable hollow suction roll or feed bar 49 journaled 20 in bearings on the frame. This feed bar has a longitudinal passage 50 therein with which the hose communicates and it is provided with perforations 50^a in two lines 25 along the surface of an enlarged central cylindrical portion 49^a thereof so that when suction is applied by means of the plunger 45, the center of a sheet engaging the roll will be drawn down on its surface so as to be carried around by the oscillatory movement 30 of the feed roll. Thus the sheets are drawn forward by the centers of their forward ends. Only one row of perforations is in use at once, the other row being closed by any desired means as by pasting a paper over it. Fig. 6 shows one row of perforations used for feeding thin paper, and Fig. 35 35 shows the other row used for heavy paper.

The oscillatory movement of the feed bar is secured by the motion of the table itself. 40 For this purpose it is provided with a rack 51 meshing with a segment or gear 52 on the feed bar. One reason for the necessity of operating the adjusting screw 30 will now be understood. When the angle is changed 45 to alter the position of the paper relative to the perforations 50^a this has to be compensated for by the adjustment of the arm 29 to cause the feed table to move properly.

The feed bar or sucker roll 49 is connected 50 with the hose by means of a fixed nozzle 55 on the cap 48. The perforation through this cap which communicates with the hose is adapted to be opened and closed by the end of the feed bar 29 which has a perforation 56 which communicates with the passage 50 therein. The cap 48 is also provided with a vent opening 57 in position to register with the perforation 56 when the feed bar turns on its axis past the position in 55 which the sheets are delivered from this feed bar. These features are shown in Figs. 4 and 5. The result is that when the feed bar is in the position shown in Figs. 5 and 6 for example, the passage 50 communicates 60 directly with the pump and is exhausted so

that the bottom sheet will be moved by the oscillation of the feed bar. When the feed bar oscillates around to the position shown in Fig. 7, the flexible hose momentarily communicates with the vent opening, and 70 after that the vent opening still communicates with the passage 50 until the cycle of operations is completed. This operation permits air to enter from the outside and entirely releases the paper from the feed 75 roll and of course there is no force to connect it therewith again until the feed roll oscillates back to the position shown in Fig. 6.

Supported by the castings or forgings 35 80 is a transverse rod 60 on which are carried a pair of pieces 61 to which a pair of guide plates 62 are fixed for the purpose of holding up the bottom sheets when the feed table recedes and holding up the projecting end 85 of the bottom sheet between the feed bar and the feed rolls 63. One of these feed rolls is journaled on a projection in fixed relation to the axis of the feed bar. The other one is journaled in a pair of members 66 which are 90 adjustable on their axes about an eccentric 67. They are fixed in adjusted positions by screws 68 as will be obvious. By this arrangement the upper feed roll is adjustable 95 toward and from the lower one to provide for feeding paper of different thicknesses or qualities.

In order properly to separate the bottom sheet which is drawn down on the feed bar 49 from the rest of the pile at each operation 100 of the feed table, the following mechanism is provided: Supported by the side frames 65 is a transverse shaft or rod, 70 on which are fixed two supports 71. Adjustment of this shaft is secured by an arm 72 on a hub 105 thereon, and a screw 73 entering the frame. Brackets 74 are adjustably fixed to these supports by screws 75. A plate 76 mounted on these supports is adapted to receive the edges of the sheets when the feed table feeds them forward and limit their forward motion. This plate is provided with arms 77 having elongated slots 78 therein along which they are adjusted on the brackets by a screw 79. This permits the plate to take different 115 positions as shown in Figs. 6 and 8.

The separating means proper consists of a plate 80 having a nose of triangular shape in cross section and provided with a curved front surface 81, the curvature of which changes from the center to the edges as will be seen by reference to Figs. 2 and 7. This nose is concave on the back side and is designed to have its front point engage the center of the bottom sheet. As this sheet 125 passes under the nose, it flattens out the sheet if it is curved. This insures the proper presentation of the sheet to the feed rolls. At the same time, the nose supports the sheets next above and gradually sepa- 130

rates them from the bottom sheet as the pile is caused to pass along over the nose. This nose is supported by the members 71 and is clamped thereon by the brackets 74. Therefore it is adjustable longitudinally by means of screws 82 entering the supports 71. It is secured in adjusted position by the screw 75.

The register table 85 may be of any usual construction. It is hung loosely on the shaft 70 by means of arms 86. The feed rolls 63 feed the paper over the tapes 87 and under guides 88 on the register table. The register table tapes and feed rolls are operated from one of the gears 13 by a train of gearing 89.

I do not claim herein the automatic tripping mechanism shown and described because that constitutes the subject matter of my divisional application thereon, Serial No. 700,185, filed May 28, 1912.

While I have illustrated and described a preferred embodiment of the invention, I am aware that many modifications may be made therein by any person skilled in the art without departing from the scope of the invention as expressed in the claims. Therefore I do not wish to be limited to all the details of construction herein shown and described, but

What I do claim is:—

1. In a bed and platen press, the combination of a feed table, longitudinal guides therefor, an oscillatable feed bar to which the forward end of the table is pivoted, means for adjusting the other end of the feed table transversely to the plane thereof, and means for reciprocating the feed table along the guides.

2. In a sheet feeding device for printing presses, the combination of a movable feed bar adapted to engage a sheet and move the same along during its own motion, a feed table supported adjacent to the feed bar in position to present one of a pile of sheets thereon to engage the surface of said feed bar, and means projecting from the feed bar toward the feed table for guiding the forward edge of a sheet on the surface of the bar, said guiding means also projecting beyond the feed bar to guide the sheet after it has advanced beyond the feed bar.

3. In a sheet feeding device the combination with a feed table, a feed bar located substantially at the end thereof, a stationary sheet separating means above the feed bar, and means for adjusting the feed table about the feed bar as a center to vary its angular relation to the bottom of the separator to permit the separation and feeding of sheets of different thickness.

4. In a sheet feeding device for printing presses, the combination of a movable feed bar adapted to engage a sheet and move the same along during its own motion, a feed table supported adjacent to the feed bar in position to present one of a pile of sheets

thereon to engage the surface of said feed bar, means for moving the feed table toward and from the feed bar, means for moving the surface of the feed bar away from the feed table, and means projecting from the feed bar toward the feed table for guiding the forward edge of a sheet on the surface of the bar, said guiding means also projecting beyond the feed bar to guide the sheet after it has advanced beyond the feed bar.

5. In a sheet feeding device for printing presses, the combination of a feed bar adapted to engage a sheet and move the same along, a feed table, and a guiding means for the sheet comprising a member having a surface substantially in registration with the surface of the feed bar that receives the sheet and projecting therefrom on opposite sides, the projection on one side extending under the sheets on the feed table, and the projection on the other side supporting the forward edges of the sheets after they have advanced beyond the feed bar.

6. In a sheet feeding device for printing presses, the combination of a feed bar adapted to engage a sheet and hold the same on its surface, a feed table having a substantially pivotal movement about the feed bar in position to present one of a pile of sheets thereon to engage the surface of said feed bar, means for oscillating the feed bar on its own axis to feed the sheets forward, and means whereby the end of the feed table opposite the feed bar can be adjusted to change the position on the feed bar to which the ends of the sheets will come.

7. In a sheet feeding device for a printing press, the combination of a feed bar oscillatable on its own axis, and provided with two sets of means at the surface thereof for engaging the bottom sheet of a pile and holding it on the feed bar while it oscillates, a feed table for supporting a pile of sheets, said feed table being supported at one end adjacent to said bar and adjustably supported at the other end, whereby the angular position of the feed table with respect to said means on the bar can be adjusted, means for reciprocating the feed table toward and from the bar, and means for oscillating the bar.

8. In a sheet feeding device for printing presses, the combination of an oscillatory feed bar having means along its surface arranged in two parallel rows for engaging the bottom sheet of a pile and holding it on the feed bar while it oscillates, a feed table, means for adjusting the relative angle of feed table and bar, whereby the sheets on the feed table can be caused to cover one or both of said rows of means, and means for oscillating the bar.

9. In a sheet feeding device for printing presses, the combination of an oscillatory feed bar having means along its surface ar-

- ranged in two parallel rows for engaging the bottom sheet of a pile and holding it on the feed bar while it oscillates, a feed table reciprocable toward and from the feed bar, means 5 for adjusting the angle of the feed table with respect to said means on the bar, whereby the sheets on the feed table can be caused to cover one or both of said rows of means, and means on the feed table for turning the feed bar on its axis when the feed table moves.
10. In a sheet feeding device for a printing press, the combination with a movable feed table, of a feed bar capable of turning on its own axis, having a passage therein 15 and provided with an enlarged cylindrical central portion having perforations leading from the surface to said passage and located in a position to receive the lower surface of the forward edge of the bottom sheet of a pile located on the feed table, means for exhausting air from said passage whereby the movement of the feed bar will draw the sheets forward by the centers of their forward edges, and stationary guides 20 and supporting plates at the sides of said enlarged portion for holding up the bottom sheets at their outer edges while they are being fed by the feed bar.
11. In a sheet feeding device for printing presses, the combination with a feed table, of a feed bar, having a passage therein provided with a plurality of rows of perforations leading from said passage to a surface of the bar which the sheets on the feed table engage, means for exhausting 30 said passage, and means for adjusting the opposite end of the feed table about the bar as a center to regulate the position of the forward edges of the sheets on the feed table with respect to said rows of perforations in the bar.
12. In a sheet feeding device for printing presses, the combination with a feed table capable of moving back and forth, of an oscillatable feed bar having a passage 45 therein provided with a plurality of adjacent rows of perforations leading from said passage to a surface of the bar which the sheets on the feed table engage when the feed table moves up toward the bar, means for exhausting said passage, and means for adjusting the opposite end of the feed table to regulate the position of the forward edges of the sheets on the feed table with respect 50 to said rows of perforations on the bar; whereby the sheets can be brought into registration with either.
13. In a sheet feeding device for printing presses, the combination with a feed table capable of moving back and forth, of an oscillatable feed bar having a passage 60 therein provided with a plurality of rows of perforations leading from said passage to a surface of the bar which the sheets on the feed table engage when the feed table
- moves up toward the bar, means for exhausting said passage, and means for adjusting the opposite end of the feed table about the bar as a center to regulate the position of the forward edges of the sheets 70 on the feed table with respect to said rows of perforations in the bar, all the perforations except those in one row being adapted to be covered by a sheet of paper pasted on the surface of the bar. 75
14. In a sheet feeding device, the combination of a feed table, a feed bar, a sheet separating means, and means for adjusting the angular relation of the feed table to the separating means and keeping them 80 at the same distance from the feed bar to permit the feeding of sheets of different thicknesses from said feed table.
15. In a sheet feeding device, the combination of a feed table, a feed bar located 85 adjacent to the end thereof, a separator for separating the bottom sheet on the feed bar from the remainder of the sheets in a pile on the feed table, and means for adjusting the end of the feed table remote from the bar to vary the angular relation thereof with the bottom of the separator to adapt the feeding device for feeding thin or thick sheets.
16. In a press feed, the combination of an 90 operating shaft, a vibratory feed table, means connected with said shaft for vibrating the feed table, a hollow movable feed bar having perforations located in position to register with the forward part of a sheet 95 when the feed table is moved up to a certain position, and means operated by said shaft for exhausting air from said bar.
17. In a sheet feeding device for printing presses, the combination of a feed bar 100 adapted to engage a sheet and move the same along, a feed table, rolls for receiving the sheets from the feed bar, a plate for positively separating a sheet from the pile 105 of sheets, said plate being mounted to swing 110 on a transverse axis at a distance from the feed bar, and means for adjusting it about said axis.
18. In a sheet feeding device for printing presses, the combination of means for 115 supporting a pile of sheets and feed bar for taking the bottom sheet therefrom and advancing it, with positive means for separating said bottom sheet from the pile, comprising a plate having a pointed nose projecting toward said feed bar in position to cover the top of the bottom sheet when advanced by the feed bar, said plate being adjustable toward and from the feed bar, and a stop plate located above said plate for 120 receiving the ends of the sheets when advanced to a position to permit the feed bar to advance the bottom sheets therefrom, said stop plate being angularly adjustable 125 with respect to the first named plate. 130

19. In a sheet feeding device, the combination of a pair of rolls for receiving a sheet, means for taking the bottom sheet from a pile and deflecting the same toward said feed rolls, a plate having a pointed nose for positively separating the bottom sheet from the pile and for receiving the pile of sheets as the same is fed forward, and a stop plate located on said plate and adjustable along the surface thereof and angularly with respect thereto for receiving the ends of the sheets when they are fed forward.

20. In a sheet feeding device, the combination of a pair of rolls for receiving a

sheet, means for taking the bottom sheet from a pile and deflecting the same toward said feed rolls, a plate for separating the bottom sheet from the pile, and a stop plate located on said plate and adjustable along the surface thereof and angularly with respect thereto for receiving the ends of the sheets when they are fed forward. 20

In testimony whereof I have hereunto set my hand, in the presence of two subscribing 25 witnesses.

HENRY A. WISE WOOD.
